UNITED STATES PATENT OFFICE.

LARS W. SODERBERG, OF ROCKFORD, ILLINOIS.

WRENCH.

1,070,550.

Specification of Letters Patent. Patented Aug. 19, 1913.

Application filed January 23, 1913. Serial No. 743,821.

To all whom it may concern:

Be it known that I, LARS W. SODERBERG, a citizen of the United States, residing at Rockford, in the county of Winnebago and 5 State of Illinois, have invented certain new and useful Improvements in Wrenches, of which the following is a specification.

The object of this invention is to construct a wrench in which the movable jaw 10 of the wrench may be adjusted or tightened upon the article being gripped by revolving the end portion of the handle of the wrench, the feeding being by screw-thread, and also to provide means engaging 15 said screw-thread which may be disengaged therefrom allowing the movable jaw to be moved quickly to any degree of opening.

In the accompanying drawings. Figure 20 1 is a longitudinal view looking at the face of the wrench, a portion of the screw-catch being broken away. Fig. 2 is a longitudinal section through the wrench on the line 2—2 of Fig. 1. Fig. 3 is a fragmentary section 25 view of the handle showing the catch disengaged from the screw. Fig. 4 is a section through the movable jaw, on the line 4—4 of Fig. 2. Fig. 5 is a transverse section on the line 5—5 of Fig. 2. Fig. 30 6 is a transverse section on the line 6—6 of Fig. 1.

The wrench body is formed of a circular tubular handle portion 7, a square neck portion 8 having the elongated opening 9, 35 and a T-shaped head 10 formed with the square portion forming the rigid square and pipe jaws.

A rod 11 is rotatable within the wrench body, has its central portion formed with 40 screw-threads as at 12, and has a circumferential groove 13 cut near its outer end. The movable jaw having the pipe jaw 14 has a reduced portion 15 which fits within the opening 9 and has the side pieces 16 riveted to the reduced portion, thereby 45 forming the lower member of square jaw and also holding the movable jaw in place allowing it to slide longitudinally in the opening. A pin 17 carried rigidly in the 50 movable jaw, lies in engagement with said groove 13, thus forming a connection between the jaw and rod 11 whereby the rod may be rotated and at the same time move the jaw.

55 The tubular and rotatable handle portion 18 telescopes the lower portion of the handle,

and has a closed end 19 having an aperture therein into which the square end 20 of rod 11 is rigidly held by the headed bolt 21.

A catch member 22 having a toothed segment portion 23 projecting through the opening 24 in the circular handle portion and engaging the teeth of the screw-thread 12, is held yieldingly in said engagement by the two flat springs 25 secured to the wrench body 1, the free ends of the springs 60 engaging the catch member. The catch member is formed with incut sides 26 to facilitate the raising of said member by hand. 70

With the catch in engagement with the screw-thread the handle portion 18 may be turned thus rotating the rod 11 and feeding the movable jaw, this method of adjustment being used when but a slight tightening is 75 required. By raising the catch free from the screw-threads the rod 11 may be moved freely by the handle portion 18 thus moving the jaw to any desired position, when the catch is dropped into engagement again 80 with the screw-thread and the wrench further tightened by the turning of handle 18.

It will be seen that with a wrench of this design very rapid adjustments can be made, and furthermore when the wrench is 85 adjusted to grip its object it can be further tightened to secure a positive grip. It will also be noted that both adjustments are made by the handle 18, the quick adjustment being the longitudinal movement 90 thereof with the catch disengaged and the other adjustment being the screw feed by revolving said handle.

I claim as my invention.

1. A wrench comprising a body having a 95 rigid jaw, a rotatable rod slidable longitudinally of the body and formed with a screw-threaded portion, a movable jaw having connection with said rotatable rod, a movable toothed-segment, and spring 100 members connecting the body and toothed segment at longitudinal ends of said toothed segment for holding said toothed segment normally into engagement with said threaded portion of the rod, and said toothed segment adapted by being moved against said action of said spring members 105 to be disengaged from said rod, thereby allowing the rod to be slidable longitudinally.

2. A wrench comprising a tubular body 110 portion having a rigid jaw formed at one end thereof, a rotatable rod slidable longi-

tudinally within the body portion and formed with a screw-threaded portion, a movable jaw having connection with the end of the rod nearest the rigid jaw, a toothed-segment in engagement with said screw-threaded portion and adapted to be disengaged therefrom, and a cylindrical handle portion telescoping the end of the tubular body portion being fixedly connected to said rod, said handle adapted when rotated, to feed said rod longitudinally and

adapted when said toothed-segment is disengaged from the rod, to allow the rod to be moved freely longitudinally.

In testimony whereof I have hereunto set my hand in presence of two subscribing witnesses.

LARS W. SODERBERG.
